Specification for Design.

Patented Apr. 17, 1917.

Application filed February 15, 1916. Serial No. 78,544. Term of patent 3½ years.

To all whom it may concern:

Be it known that I, JOHN FRANCIS HANBURY, a citizen of the United States of America, residing in 500 West One Hundred and Seventy-third street, borough of Manhattan, city, county, and State of New York, have invented a new, original, and ornamental Design for an Insignia, Button, Pin, Fob, Box-Top, Paper-Weight, or Similar Articles, of which the following is a specification, reference being had to the accompanying drawing, forming a part thereof.

The design as used will be in colors, red, white and blue. The stars white on a blue ground and the stripes alternating white and red.

I claim:

The ornamental design for an insignia, button, pin, fob, box top, paper weight or similar articles as shown.

JOHN FRANCIS HANBURY.
